UNITED STATES PATENT OFFICE.

FREDERIC L. WANKLYN, OF MONTREAL, QUEBEC, CANADA.

RAILWAY-TRACK SIGNAL.

Application filed June 2, 1923. Serial No. 643,113.

To all whom it may concern:

Be it known that I, FREDERIC L. WANKLYN, of the city of Montreal, Province of Quebec, Dominion of Canada, a subject of the King of Great Britain, have invented certain new and useful Improvements in Railway-Track Signals; and I do hereby declare that the following is a full, clear, and exact description thereof.

10 My invention relates particularly to torpedoes for use along the railway track as signals warning a train approaching another train which is stalled, or any other point of danger. It relates particularly to that 15 structure of the torpedo by which the torpedo is fastened to the rail, this structure in my present invention being of necessity possessed of maximum holding power within the capacity of the materials employed.

20 The invention includes a container adapted to contain the relatively large bulk necessitated by the requirement in the torpedo to produce a loud noise, a brilliant flash, a pungent odour and a smoke in contradistinction to those torpedoes which produce a noise only. I combine with this container a resilient wire clip of particular construction for fastening the torpedo to the head of a rail. This clip consists of a wire arch 25 presenting a straight top, to facilitate pivotal connection to the bottom of the container, and straight sides adapted to lie flat on the sides of the rail head, such legs converging slightly and being united to the 30 straight top by relatively wide curved shoulders to present a form set to possess maximum inherent resilience and strength. The extremities of the legs have semi-circular form terminating in straight ends disposed 35 parallel to the legs and having conical teeth at their ends for the purpose of biting into the surface of the under shoulder of the rail head.

For full comprehension, however, of my 40 invention reference must be had to the accompanying drawings in which similar reference characters indicate the same parts, and wherein:

Figure 1 is a transverse sectional view of 45 a rail head with my improved torpedo clip in place;

Figure 2 is an end elevation of the torpedo;

Figure 3 is a side elevation of the torpedo; 50 and

Figure 4 is a detail elevation of the resilient wire clip.

The container in order to provide the necessary properties and qualifications to accommodate a relatively large charge such as required to produce noise, a flash of light, a pungent odour and a smoke consists of thin sheet pyralin or pyroxylin, as indicated at *b* and the inflammable materials for detonation, flash, etc. are indicated at *c*, *d*. To fasten securely to the rails this container of relatively large capacity I employ a comparatively stiff wire in the form of an arch with straight top *d* pivotally secured to the underside of the container the securing means consisting of a strip of fabric or other suitable fastening, straight legs *e*, round shoulders *f* presenting a broad curve and the extremities of the legs being bent to semi-circular form *g* terminating in straight portions *h* with conical teeth *k*. The straight portions *h* are disposed parallel to the legs *e*.

This combination of curves and straight portions produces in the clip a resilient property adapted to absorb the vibrations of the rail without displacement of the teeth from the particular points on the shoulders of the rail with which they come into engagement when the torpedo is set in place, the straight portions *h* coacting with the semi-circular curves *g* to enable a trainman to, while holding the container securely in his hand, strike the clip onto the head of the rail, these curved extremities and straight portions riding over the sides and snapping into position with the teeth biting into the metal of the underside of the shoulder of the rail head.

This particular form of clip effectively holds the torpedo in place notwithstanding its increased bulk because of the materials in addition to the detonator contained within it. Although I prefer teeth of conical form for the biting ends of the clip, pyramidal or chisel points do not depart from the spirit of my invention.

What I claim is as follows:

1. The combination with a railway signal torpedo container containing a substance exploded by concussion, of a resilient wire clip for fastening the container to a rail head, such clip consisting of an arch presenting a straight top and straight converging side legs united to the top by relatively wide curved shoulders and the extremities of

the legs consisting of semi-circular curves terminating in straight ends with teeth for biting into the surface of the underside of the rail head, and means pivotally connecting the straight top portion of the clip to the underside of the container.

2. The combination with a railway signal torpedo container containing a flash powder and a detonator, of a resilient wire clip for fastening the container to a rail head, such clip consisting of an arch presenting a straight top and straight converging side legs united to the top by relatively wide curved shoulders, and the extremities of the legs consisting of semi-circular curves terminating in straight ends with teeth for biting into the surface of the underside of the rail head, and means pivotally connecting the straight top portion of the clip to the underside of the container.

3. The combination with a railway signal torpedo container containing a substance exploded by concussion, of a resilient wire clip for fastening the container to a rail head, such clip consisting of an arch presenting a straight top and straight converging side legs united to the top by relatively wide curved shoulders, and the extremities of the legs consisting of semi-circular curves terminating in straight ends with conical

teeth for biting into the surface of the underside of the rail head, the said straight ends being each disposed in a plane parallel to its legs, and means pivotally connecting the straight top portion of the clip to the underside of the container.

4. The combination with a railway signal torpedo container containing a flash powder and a detonator, of a resilient wire clip for fastening the container to a rail head, such clip consisting of an arch presenting a straight top and straight converging side legs united to the top by relatively wide curved shoulders and the extremities of the legs consisting of semi-circular curves terminating in straight ends with conical teeth for biting into the surface of the underside of the rail head, the said straight ends being each disposed in a plane parallel to its legs and means pivotally connecting the straight top portion of the clip to the underside of the container.

In testimony whereof I have signed my name to this specification in the presence of two witnessess.

FREDERIC L. WANKLYN.
